UNITED STATES PATENT OFFICE.

HENRY D. JUSTI, OF PHILADELPHIA, PENNSYLVANIA.

DENTAL PLUGGER.

SPECIFICATION forming part of Letters Patent No. 224,595, dated February 17, 1880.

Application filed September 23, 1879.

To all whom it may concern:

Be it known that I, HENRY D. JUSTI, of Philadelphia, in the county of Philadelphia and State of Pennsylvania, have invented certain Improvements in Dental Pluggers, of which the following is a specification.

My invention relates to improvements upon the instrument for which Letters Patent were granted to me bearing date May 13, 1879, and numbered 215,226; and the improvements consist in the interposition of a spring between the rotary cam or hammer and the stem or tool-shank for the purpose of rendering the action noiseless, and in an adjustable collar and spring to control the force of the blow.

Figure 1 represents a side elevation of my improved instrument; Fig. 2, a longitudinal central section of the same; Fig. 3, a cross-section on the line *xx*.

In its general construction and mode of operation the instrument is similar to that shown in my original patent; and it consists of a revolving eccentric hammer, A, arranged to act upon the upper end of a sliding shank or spindle, B, which latter is mounted in a tubular body, C, jointed to the hammer-sustaining frame D.

In the original instrument the hammer delivered its blow directly upon the shank or spindle, thereby producing an unpleasant hammering noise. To overcome this trouble I now locate between the hammer and the upper end of the spindle a flat spring, E, one end of which is secured to the body C, as shown. When the spindle is forced upward to receive a blow from the hammer the spring is elevated, as shown in Fig. 3, so that the hammer, encountering the spring at a point one side of the spindle, will ride easily and smoothly over its inclined yielding surface, forcing it downward, and causing it, in turn, to carry down the spindle in a practically noiseless manner. In this manner I am enabled to give the instrument a much smoother, easier, and more quiet action, without in the least impairing its efficiency. The form and attachment of the spring may, if desired, be modified, provided its mode of action is not changed.

In my original instrument a spring urged the spindle or stem constantly upward within

the path of the hammer, so that the rotation of the latter caused the movement of the spindle when the instrument was not in use. I now reverse this arrangement, and so dispose of the parts that the hammer delivers its blow only when the tool is pressed against the tooth of the patient. This construction will be readily understood on reference to Fig. 2.

The lower end of the tubular body C is threaded to receive an exterior cap or collar, F, the lower end of which is chambered out or counterbored to receive the enlarged lower end of the spindle or shank B, as shown. The spindle is of reduced diameter from its upper end to the point where it enters the collar F, at which point it is enlarged, as shown, so as to form a shoulder, e. This shoulder, striking the bottom of the recess in the collar, thereby limits the ascent of the spindle, and thus determines the distance which the spindle will be moved by the hammer, and consequently the force of the blow imparted to it. By screwing the collar upward the force of the blow may be increased, and by screwing it downward the force may be diminished.

In order to prevent the collar from being moved by the jar and concussion of the instrument, the collar is notched on the outside and the tubular body provided with a spring arm or catch, d, to engage therein, as shown.

In order to urge the spindle downward out of the path of the hammer when the instrument is not in use, a spiral spring is seated into an annular recess in the spindle and arranged to bear against the interior of the collar, as shown. This spring presses the spindle downward whenever the tool is not in use; but a slight downward pressure of the instrument upon the tooth forces the spindle upward in position to receive the blows of the hammer. The spindle is retained in place in the body by means of a screw, e, inserted through the side of the body into an annular groove in the spindle, as shown, the groove being made of the proper width to permit the endwise movement of the spindle, and of such depth as to allow a free rotation of the same.

It will be observed that in the present instrument the spring acts to urge the spindle away from the hammer, instead of toward the same, as in my original instrument. This ar-

angement admits of the hammer running continuously without noise and without acting upon the spindle until a downward pressure is brought to bear upon the instrument, and 5 also admits of the force of the blow being modified by simply changing the pressure, and without changing the devices by which a limit is fixed as to the force of the blow.

I do not claim, broadly, the combination of 10 a hammer, a spindle, and a spring tending to urge the spindle away from the hammer, for I am aware of a plugger wherein the pressure of the spindle toward the reciprocating hammer served to actuate intermediate mechanism 15 through which the hammer-actuating devices were set in motion. In the arrangement above alluded to it is necessary that the hammer shall remain at rest when the instrument is not in use, for the reason that otherwise the 20 hammer would keep up a constant annoying and destructive pounding within the instrument, and this necessity, in turn, renders the use of the intermediate devices between the spindle and hammer unavoidable.

25 My arrangement differs from that above described in that I use a rotary instead of a reciprocating hammer, and so arrange and organize the parts that the rotary hammer is permitted to run continuously and noiselessly 30 without acting upon the spindle until the latter is pressed backward, whereupon it is brought within range of and acted upon by the hammer without having recourse to intermediate parts or devices. The advantages 35 gained are greater simplicity, reduced cost, absence of noise, and greater rapidity of action.

Having described my invention, what I claim is—

1. The combination of the rotary hammer, 40 sliding spindle, and an intermediate spring to receive the blow, substantially as described and shown.

2. The combination, in a dental plugger, of 45 the rotary hammer, the sliding spindle, and the flat metal spring to receive the blow, substantially as described.

3. The combination of the body, the rotary hammer, the sliding spindle provided with a shoulder or projection, the spring arranged to 50 urge the spindle away from the hammer, and the adjustable collar to limit the movement toward the hammer.

4. A dental plugger consisting of a body 55 or hand-piece, a sliding spindle, a rotary eccentric-hammer mounted in the body to act against the spindle, and a spring urging the spindle away from the hammer, said parts being organized and arranged as described and shown, so that the rotary hammer may run 60 continuously and noiselessly and without striking any of the parts until the spindle is forced back in use.

5. The combination of the body, the collar adapted to regulate the movement of the spindle, and the spring-catch or locking device. 65

6. The combination, in a plugger, of the body, the shouldered endwise-moving spindle provided with the annular recess, the spring seated in said recess, and the adjustable collar. 70
